SOLDERING IRON TIP CLEANER

Chamberlain Ferry, Lyme, Conn., assignor to Electric
Soldering Iron Company, Inc., Deep River, Conn., a
corporation of Connecticut

Filed Jan. 17, 1966, Ser. No. 647

Term of patent 14 years

(Cl. D9—6)

fig. 1

fig. 2

fig. 3

FIG. 1 is an isometric view of a soldering iron tip cleaner showing my new design;

FIG. 2 is an enlarged top view of the soldering iron tip cleaner of FIG. 1; and

FIG. 3 is an enlarged elevational view of the soldering iron tip cleaner of FIG. 1.

The undisclosed bottom of the soldering iron tip cleaner is substantially flat and plain.

I claim:

The ornamental design for a soldering iron tip cleaner, as shown and described.
